Primary Examiner — Brett Miller*Assistant Examiner* — Rani J Abdallah(74) *Attorney, Agent, or Firm* — Paul D Bangor, Jr., Esquire; Clark Hill, PLC(57) **CLAIM**

The ornamental design for a bottle, as shown and described.

DESCRIPTION

FIG. 1 is a top, front perspective view of the bottle of the present design;

FIG. 2 is a right elevational view thereof;

FIG. 3 is a left elevation view thereof;

FIG. 4 is a rear elevational view thereof;

FIG. 5 is a front elevational view thereof;

FIG. 6 is a top plan view thereof; and,

FIG. 7 is a bottom plan view thereof.

The broken lines shown illustrate portions of the bottle that form no part of the claimed design.
